US0D1085424S

(12) **United States Design Patent** (10) **Patent No.:** **US D1,085,424 S**
Weston et al. (45) **Date of Patent:** **** Jul. 22, 2025**

(54) **FENESTRATED HUMAN PLACENTAL ALLOGRAFT**

(71) Applicant: **BioStem Technologies, Inc.**, Pompano Beach, FL (US)

(72) Inventors: **Wendy W. Weston**, Coral Springs, FL (US); **Jason V. Matuszewski**, Boca Raton, FL (US); **Taylor J. Sabol**, Pompano Beach, FL (US)

(73) Assignee: **BioStem Technologies, Inc.**, Pompano Beach, FL (US)

(**) Term: **15 Years**

(21) Appl. No.: **29/860,417**

(22) Filed: **Nov. 18, 2022**

(51) **LOC (15) Cl.** **24-02**

(52) **U.S. Cl.**

USPC **D24/189**

(58) **Field of Classification Search**

USPC D24/188-190, 200, 206, 108; D29/100, D29/108, 120.1, 121.1, 121.2

CPC A61K 35/50; A61K 41/10; A61L 27/3604

(57) **CLAIM**

The ornamental design for a fenestrated human placental allograft, as shown and described.

DESCRIPTION

FIG. 1 is a top perspective view of the new design for a fenestrated human placental allograft;

FIG. 2 is a bottom perspective view thereof;

FIG. 3 is a top view thereof;

FIG. 4 is a bottom view thereof;

FIG. 5 is a front view thereof;

FIG. 6 is a back view thereof;

FIG. 7 is a right side view thereof; and,

FIG. 8 is a left side view thereof.

In the drawings, the broken lines show portions of a fenestrated human placental allograft that form no part of the claim.

The claim is limited to the solid lines.

1 Claim, 3 Drawing Sheets
